CHARLES L. RHODES, OF PROVIDENCE, RHODE ISLAND, ASSIGNOR TO BUGSEE & NILES CO., OF PROVIDENCE, RHODE ISLAND, A CORPORATION OF RHODE ISLAND.

BRACELET-CLASP.

1,115,236.

Specification of Letters Patent. Patented Oct. 27, 1914.

Application filed April 30, 1914. Serial No. 835,552.

To all whom it may concern:

Be it known that I, CHARLES L. RHODES, a citizen of the United States, residing at Providence, in the county of Providence and 5 State of Rhode Island, have invented a new and useful Improvement in Bracelet-Clasps, of which the following is a specification.

This invention relates to certain new and useful improvements in bracelet clasps, and 10 the primary object thereof is to provide a clasp, which is particularly adapted to link bracelets, and which can be incorporated therein so as to be practically invisible, and to also not interfere with the flexibility of 15 the bracelet.

Further, the invention aims to provide a clasp which can be easily operated to open position, and easily locked and which will effectively hold the parts in locked position.

20 Still further the invention aims to provide a clasp which is of simple and economical construction, and in which the parts are effectively held against accidental disengagement.

25 A still further object of the invention is to guard against accidental disengagement of the parts by requiring one of the parts to be moved to a position at substantially right angles to the other part before such parts 30 can be separated, thus reducing to a minimum any possibility of the parts being separated without intent.

In the drawings—Figure 1 is a top plan view of the two ends of a link bracelet to 35 which the present invention is applied. Fig. 2 is a central longitudinal section of Fig. 1. Fig. 3 is a view similar to Fig. 1, showing the parts in position preparatory to unlocking, and Fig. 4 is an enlarged sectional 40 view taken on the line 4—4 of Fig. 2.

The bracelet depicted in the drawings may be composed of any number of links, and 45 may be of any structure, the present showing being that of a type of link bracelet in which the units 1 are connected by links 2. The catch consists of a member formed at one end with an opening 4, through which a pin 3 is passed, the member having a slotted portion 5 which is extended at 6 through 50 one of the sides of the member to form a catch proper 7 which is provided with a locking finger 8. The catch proper 7 is formed with a cutaway part 9 located to the rear of finger 8 and is further provided with 55 a projection 10 which has a serrated or

roughened outer face to enable the finger-nail of the user to be engaged therewith so as to depress the catch proper in releasing or unlocking of the parts. The slot 5 and extension 6 thereof provides the opposite 60 end of the catch member with a hook 11, which engages a pin 3' on the opposite end of the bracelet. The unit 1 at said opposite end of the bracelet is provided with opposite plates 12 and 13, the outer of which 65 designated 12 is slotted at 14 so as to receive in the slot the finger 8, as depicted in Fig. 2 of the drawings. The inner plate 13 is longer than the outer plate 12, so that it will engage under the side 15 of the catch 70 as shown in Fig. 2 and hold the catch against opening movement.

The length of the plate 13 is such that when the unit is moved so as to bring its pin 3' to register with the opening 6, the 75 plate 13 will be engaged with the side 15 of the catch so as to prevent the latter from being disengaged until the unit is moved at right angles to the catch 2, in which position the pin 3' may pass through the opening 6 and thus disengage the parts. The plates 12 and 13 may be soldered in position.

In operation, when it is desired to move the parts from the locked position shown in 80 Fig. 2, to unlocked position, the catch is depressed so as to move finger 8 out of the slot 14, whereupon the pin 3' can be moved to engage the hook 11, then the unit having the plates 12 and 13 attached thereto 85 is turned so as to move pin 3' thereof about hook 11 as a pivot until said unit occupies an angular relation to the catch member, as shown in dotted lines in Fig. 3, when same is slid to cause the pin 3' to pass 90 through the opening 6, which effects disengagement of the parts. Pin 3' preferably snaps past the finger 8 and the free end of hook 11 which combined with the fact that the unit bearing the pin 3' must be 100 moved at an angle to the catch to effect disengagement of the parts provides a lock which is proof against accidental disengagement for all practical purposes.

Having thus described my invention, I 105 claim as new and desire to secure by Letters Patent—

1. In a bracelet clasp, a catch consisting of a member pivoted at one end to one end of the bracelet and having a slotted portion 110

and an opening which extends from the slot through one side of the member to form a hook and a catch proper, said catch proper having a finger projecting outwardly from its free end and also having a serrated projection located to the rear of the finger and being formed with a cutaway part between the finger and projection, a pin on the opposite end of the bracelet to engage 10 the hook, and a pair of plates secured on opposite sides of the last named end of the bracelet, one of said plates being longer than the other, and the outer of said plates being formed with an opening through 15 which the finger of the catch projects, the longer of said plates engaging the inner side of the catch member to prevent the pin from passing through the opening of the catch member except when the pin and 20 therewith the long plate, is turned in the arc of a circle to allow the pin to register with the said opening and be passed through the latter.

2. In a bracelet clasp, a catch pivoted to 25 one end of a bracelet, said catch having a catch proper and a hook spaced from the catch proper, a pin on the other end of the bracelet engageable with the hook, and means on said last named end of the bracelet 30 whereby the pin cannot be disengaged from

the hook until said last named end of the bracelet is moved at an angle to the other end thereof to cause the pin to first register with and then be passed through said space between the hook and catch proper, said 35 means having a part thereof which receives the catch proper to lock the bracelet.

3. In a bracelet clasp, a catch pivoted to one end of a bracelet, said catch having a catch proper and a hook spaced therefrom, a 40 pin on the other end of the bracelet engageable with the hook, and a pair of plates on the last named end of the bracelet one of which is formed to receive the catch proper and the other of which engages the inner 45 side of the catch and which prevents the pin from being disengaged from the hook until the end of the bracelet which carries the pin is moved at an angle to the other end of the bracelet to cause the pin to first 50 register with and then be passed through said space between the hook and catch proper.

In testimony whereof I have signed my name to this specification in the presence of 55 two subscribing witnesses.

CHARLES L. RHODES.
